UNITED STATES PATENT OFFICE.

FRANK G. CALDWELL, OF WHEELING, WEST VIRGINIA.

SHEET-METAL ROOFING.

SPECIFICATION forming part of Letters Patent No. 403,415, dated May 14, 1889.

Application filed October 16, 1888. Serial No. 288,218. (No model.)

To all whom it may concern:

Be it known that I, FRANK G. CALDWELL, a citizen of the United States, residing at Wheeling, in the county of Ohio and State of 55
5 West Virginia, have invented new and useful Improvements in Sheet - Metal Roofing, of which the following is a specification.

The invention relates to metallic roofing wherein sheet-metal plates are applied to and 10 engaged with the longitudinal edges of separated or spaced sheathing-boards secured to purlins.

The objects of this invention are to improve such character of roofing, to provide novel 15 caps between the separated wooden sheathing-boards, which not only serve as gages for properly spacing the sheathing-boards as they are secured to the purlin, but also receive the flanged edges of the sheet-metal roofing-plates, 20 and to provide a novel construction whereby the flanged roofing-plates can be conveniently and easily inserted lengthwise into engagement with independent metal caps and the longitudinal edges of the wooden sheathing- 25 boards without the flanges of the roofing-plates touching the wooden boards, but, on the contrary, having sliding contact with the smooth surfaces of the independent caps located between the spaced wooden boards.

30 To such ends the invention consists in the novel construction of the roofing-plates and the independent metal caps to engage beveled and undercut sheathing - boards, as herein-after specifically described and claimed, reference being made to the accompanying drawings, in which—

Figure 1 is a perspective sectional view of a portion of sheet-metal roofing embodying my invention; Fig. 2, a detail perspective view 40 of one of the metal caps, and Fig. 3 a detail perspective view of one of the sheet-metal roofing-plates.

In order to enable those skilled in the art to make and use my invention, I will now describe the same in detail, referring to the 45 drawings, where the numeral 1 indicates a purlin, of which there may be any number, and 2 the sheathing-boards, each of which has its opposite edges beveled, as at 3, and is 50 provided in its lower side with rectangular under-cuts or rabbets 4. The independent

caps are each composed of a rectilinear sheet of metal having a substantially flat and extended head, 5, and bent inwardly to form upper walls, 6, that project toward each other, 55 and are respectively bent outwardly to form divergent wings 7, leaving a contracted space or mouth, 8, between the walls 6, from whence the divergent wings extend. The metallic roofing-plates 9 are substantially flat on their 60 upper surfaces, and at each side are bent inwardly to form beveled walls 10, which are turned laterally in opposite directions to provide substantially horizontally - extending flanges 11, the walls 10 and flanges 11 corre- 65 sponding approximately to the angles formed by the divergent wings 7 and walls 6 of the caps.

A sheathing-board 2 being secured to the purlin, a metal cap is inserted so that it enters the under-cut or rabbet 4, and then another sheathing-board is secured to the purlin so that its beveled side enters the angle formed by the wall 6 and wing 7 of the cap, and so on across the superstructure of the roof. By this means the metal caps, being of substantially similar size and form, serve as gages to properly space the sheathing - boards, thereby avoiding accurate measurements and skilled workmanship. The divergent wings of the caps may be secured to the beveled 75 edges 3 of the sheathing-boards, if desired, by nails or otherwise, and when the caps are placed in position between the sheathing-boards, as explained, the metal roofing-plates are inserted lengthwise by sliding them into 80 engagement with the caps, so that the beveled walls 10 rest on the divergent wings 7 and the lateral flanges 11 enter between the top walls, 6, and the heads 5 of the caps, as clearly shown in Fig. 1. The independent 85 caps being placed in position between the sheathing-boards, as shown, the roofing-plates, when inserted, have no contact with the wooden boards at the bevels 10 and flanges 11, but, on the contrary, have a sliding contact with the smooth metallic surfaces of the caps, thereby enabling the roofing-sheets to be inserted lengthwise into place with far greater facility and convenience than where the flanged roofing-plates are inserted lengthwise 90 into direct engagement with beveled sheathing-boards.

The roofing-plates are lapped at the eaves and comb of the roof in any usual or desired manner.

What I claim is—

- 5 1. The combination of the independent caps, each composed of a sheet of metal having a head, 5, inwardly-extending top walls, 6, and divergent wings 7, with the sheet-metal roofing-plates having beveled sides 10 and lateral flanges 11, to slide lengthwise into engagement with the top walls and wings of the caps, substantially as described.
- 10 2. A roofing consisting of the sheathing—

boards having their opposite side edges beveled and rabbeted, the caps each composed of a sheet of metal having a head, inwardly-extending top walls and diverging wings, and the roofing-plates having side bevels and lateral flanges engaging the top walls and wings of the caps, substantially as described.

In testimony whereof I affix my signature in presence of two witnesses.

FRANK G. CALDWELL.
